(57) **CLAIM**

The ornamental design for a projectile toss target game apparatus, as shown and described.

DESCRIPTION

FIG. 1 is a side perspective view of a projectile toss target game apparatus, showing my new design;

FIG. 2 is an opposite side perspective view thereof;

FIG. 3 is a front perspective view thereof;

FIG. 4 is a rear perspective view thereof;

FIG. 5 is a top plan view thereof;

FIG. 6 is a bottom plan view thereof;

FIG. 7 is another perspective view thereof with a lid in a closed position;

FIG. 8 is a front elevation view thereof;

FIG. 9 is a rear elevation view thereof;

FIG. 10 is a left side elevation view thereof;

FIG. 11 is a right side elevation view thereof;

FIG. 12 is a perspective view thereof in a stowed position; and,

FIG. 13 is a bottom plan view thereof.

Broken lines illustrate portions of the projectile toss target game apparatus which do not form a part of the claimed design.

1 Claim, 13 Drawing Sheets
